DESIGN FOR A COMBINED VALET CABINET AND COAT HANGER

Edward E. Burr, Chicago, Ill.

Application March 16, 1944, Serial No. 112,917

Term of patent 3½ years

(Cl. D33—19)

To all whom it may concern:

Be it known that I, Edward E. Burr, a citizen of the United States, residing at Chicago, in the county of Cook and State of Illinois, have invented a new, original, and ornamental Design for a Combined Valet Cabinet and Coat Hanger, of which the following is a specification, reference being had to the accompanying drawing, forming a part thereof.

Fig. 1 is a front and side perspective view of the combined valet cabinet and coat hanger, showing my new design; and

Fig. 2 is a rear and opposite side perspective view thereof, the coat hanger element being shown in its collapsed position.

I claim:

The ornamental design for a combined valet cabinet and coat hanger, as shown and described.

EDWARD E. BURR.
